CLAIM

The ornamental design for a freestanding ladder storage rack, as shown and described.

DESCRIPTION

FIG. 1 is a front perspective view of a first embodiment of a freestanding ladder storage rack showing my new design having a shelf in an upright position;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1;

FIG. 8 is a front perspective view of a series of freestanding ladder storage racks of FIG. 1 holding ladders, boxes and PVC piping.

FIG. 9 is a front perspective view of a second embodiment of a freestanding ladder storage rack showing my new design having a shelf in a downward position;

FIG. 10 is a front view of FIG. 9;

FIG. 11 is a rear view of FIG. 9;

FIG. 12 is a left side view of FIG. 9;

FIG. 13 is a right side view of FIG. 9;

FIG. 14 is a top view of FIG. 9;

FIG. 15 is a bottom view of FIG. 9; and,

FIG. 16 is a front perspective view of a series of freestanding ladder storage racks of FIG. 9 holding ladders, boxes and PVC piping.

The broken lines depict portions of the article and environment that form no part of the claimed design.
